UNITED STATES PATENT OFFICE.

FREDERICK K. STONE, OF CHICAGO, ILLINOIS, ASSIGNOR TO THE WAVERLY COMPANY, OF INDIANAPOLIS, INDIANA, A CORPORATION OF INDIANA.

DESIGN FOR A VEHICLE-BODY.

44,696.

Specification for Design.

Patented Sept. 23, 1913.

Application filed May 2, 1913. Serial No. 765,135. Term of patent 7 years.

To all whom it may concern:

Be it known that I, FREDERICK K. STONE, a citizen of the United States, residing at Chicago, in the county of Cook and State of Illinois, have invented a certain new, original, and ornamental Design for a Vehicle-Body, of which the following is a specification, reference being had to the accompanying drawing, forming part thereof.

The figure is a view in side elevation of a vehicle body, showing my new design.

I claim:

The ornamental design for a vehicle body, as shown.

In witness whereof, I have hereunto set my hand and seal at Chicago, Illinois, this 19th day of July, A. D. one thousand nine hundred and twelve.

FREDERICK K. STONE. [L.S.]
